US00D974677S

(12) **United States Design Patent** (10) **Patent No.:** **US D974,677 S**
(45) **Date of Patent:** **** Jan. 3, 2023**

(54) **APPARATUS FOR PET HAIR REMOVAL**

(71) Applicant: **Towerstar Pets, LLC**, Malvern, PA (US)

(72) Inventors: **Fernando Becattini, Jr.**, Malvern, PA (US); **Jacquelyn N. Becattini**, Malvern, PA (US); **Fernando Becattini, Sr.**, Devon, PA (US); **Steve A. Copeland**, Barrie (CA); **Nicholas Teixeira**, Angus (CA)

(73) Assignee: **TOWERSTAR PETS, LLC**, Malvern, PA (US)

(**) Term: **15 Years**

(21) Appl. No.: **29/842,144**

(22) Filed: **Jun. 10, 2022**

(51) LOC (14) Cl. **30-99**

(52) U.S. Cl.

USPC **D30/159**; D30/158

(57) **CLAIM**

The ornamental design for an apparatus for pet hair removal, as shown and described.

DESCRIPTION

FIG. 1 is a front, top, right side isometric perspective view of an apparatus for pet hair removal in accordance with our design;

FIG. 2 is a front, top, left side isometric perspective thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines illustrate portions of the apparatus for pet hair removal which form no part of the claimed design.
